United States Patent [19]

Khemka

[11] Patent Number: Des. 281,147

[45] Date of Patent: ** Oct. 29, 1985

[54] **THERMOCHROMIC FINGER THERMOMETER**

[75] Inventor: **Kailash C. Khemka**, Indianapolis, Ind.

[73] Assignee: **Bio-Temp Products, Inc.**, Indianapolis, Ind.

[*] Notice: The portion of the term of this patent subsequent to Aug. 10, 1996 has been disclaimed.

[**] Term: **14 Years**

[21] Appl. No.: **402,911**

[22] Filed: **Jul. 29, 1982**

[57] **CLAIM**

The ornamental design for a thermochromic finger thermometer, as shown and described.

DESCRIPTION

FIG. 1 is a front elevational view of a thermochromic finger thermometer showing my new design with a typical temperature indication of 80 degrees; FIG. 2 is a left side elevational view thereof; FIG. 3 is a right side elevational view thereof; FIG. 4 is a top plan view thereof; FIG. 5 is a rear elevational view thereof; FIG. 6 is a bottom plan view thereof; FIG. 7 is a front elevational view of another embodiment of my new design of FIGS. 1-6 with a typical temperature indication of 70 degrees, all other views corresponding to FIGS. 2-6.

It is understood that each temperature indication shown in FIGS. 1 and 7 has a rectangular area adjacent thereto which is visible substantially only when the liquid crystal is at that temperature; hence, normally only one rectangle is visible at any given time.
